US00D970525S

(12) **United States Design Patent** (10) **Patent No.:** **US D970,525 S**
Sun et al. (45) **Date of Patent:** **** Nov. 22, 2022**

(54) **DISPLAY SCREEN OR PORTION THEREOF
WITH GRAPHICAL USER INTERFACE**

(71) Applicant: **Lenovo (Beijing) Co., Ltd.**, Beijing (CN)

(72) Inventors: **Yao Sun**, Beijing (CN); **Di Wang**, Beijing (CN)

(73) Assignee: **Lenovo (Beijing) Co., Ltd.**, Beijing (CN)

(**) Term: **15 Years**

(21) Appl. No.: **29/791,917**

(22) Filed: **Feb. 18, 2022**

Related U.S. Application Data

(62) Division of application No. 35/509,471, filed on Mar. 12, 2020 (U.S. filing date under 35 U.S.C. 384), and having an international filing date of Mar. 12, 2020, now Pat. No. Des. 947,219.
